UNITED STATES PATENT OFFICE.

ALFRED SCHLOSSHAUER, OF BERLIN, GERMANY.

CENTRAL LUBRICATING APPARATUS FOR STIFF LUBRICANTS.

Application filed March 9, 1927, Serial No. 173,939, and in Germany December 16, 1925.

For the central distribution of oil lubricating apparatus with piston pumps have become known, in which with the aid of a common cam disk the pump pistons are moved up and down and the pressure-channels as well as the motion-channels of the pumps are positively controlled by a cock body connected to the cam disk. The adaptation of such form of construction to central lubricating apparatus for stiff lubricant is difficult in respect of the uniform and secure feeding of the stiff lubricant into the several pump cylinders. As the stiff lubricant does not flow into the pump cylinders like oil, means must be provided, when constructions commonly used for oil have to be used, which supplies from the lid pressure to the stiff lubricant in the reservoir. Such mechanisms increase not only the cost of manufacture of the lubricating apparatus but they make difficult the adjusting of the conveying efficiency of the several pumps so that it remains permanently uniform.

In order to suck the stiff lubricants directly from the reservoir, the suction channel common to all pumps ends, according to the invention, in a suction-head arranged in proximity to the bottom of the reservoir and rotatably mounted and positively connected with the rotary cam disk serving as driving elements for the pistons, and covered by a screen.

This arrangement of the suction head in the reservoir for the stiff lubricant prevents the formation of a funnel in the stiff lubricant and merging at the upper end into the free space of the reservoir so that through this funnel air would be conveyed instead of lubricant. The suction-head which is permanently rotated is forced to withdraw stiff lubricant permanently at other points so that it is prevented from sucking a funnel out of the stiff lubricant. Consequently the comparatively low sucking force of a small pump piston is sufficient to fill securely the whole pump cylinder with the required quantity of stiff lubricant prior to the reversing to working stroke.

An embodiment of the invention is shown by way of example in cross section in the only figure of the accompanying drawing.

The cam disk 4 is driven from the driving worm 1 through the intermediary of a worm wheel 2, 3 the cam disk being made in one

piece with the worm wheel 2 and it merges at 55 the top into a cock body 5. The cam disk 4 alternately raises and lowers the pistons 7, the cock body 5 connecting positively the piston cylinders 10 alternately with the supply channel 11 and with the pressure channel 12 by means of its passages 8 and 9. Central lubricating apparatus of this type have been hitherto used exclusively for oil.

This invention has for its object to make apparatus of this type adapted to be used 65 for stiff lubricant without substantial mechanical additions. With this object in view the suction channel 11, which is designed to supply the stiff lubricant from the reservoir 13, comprises a suction head 14. This suction head has no suction holes in the direction of the central line of the reservoir 13. All these suction holes are arranged close to the wall of the reservoir 13. The suction head 14, being further connected with the cam disk 70 4 or with the cock body 5, is permanently rotated. In this manner it is ensured that in proximity to the suction openings neither funnels can be formed which extend through the lubricant up to the air space above the 75 same, nor even small air-filled spaces. Whilst the oil, owing to its little viscosity, flows in continuously and avoids formation of hollow spaces, stiff lubricant has the tendency to form such hollow spaces and funnels which, owing to the little volume of the 80 several pump bodies and to the comparatively low suction force resulting therefrom, would make the entire conveying efficiency 85 and lubricating work of the apparatus in- 90 calculable and uncertain.

I claim:—

In a central lubricating apparatus for stiff lubricant in combination with a reservoir for stiff lubricant, a number of piston pumps, a driving mechanism, a cock plug made in one piece with said driving mechanism and having a suction channel common to all piston cylinders, a suction head in said cock plug rotating with the same and connected with said suction channel, all the perforations of said suction head being arranged on the sides of said suction head which projects into said reservoir so that the stiff lubricant is permanently sucked off from other 100 points of the mass in said reservoir.

In testimony whereof I affix my signature.

ALFRED SCHLOSSHAUER.
